UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A HARROW-FRAME.

SPECIFICATION forming part of Design No. 29,314, dated September 6, 1898.

Application filed August 3, 1898. Serial No. 687,647. Term of patent 14 years.

To all whom it may concern:

Be it known that I, GEORGE W. REAM, a citizen of the United States, residing at Canton, Ohio, have invented and produced a new and original Design for Harrow-Frames, of which the following is a specification, reference being had to the accompanying drawings, forming a part thereof.

In the drawings, Figure 1 is a plan of the harrow-frame, while Fig. 2 is a side elevation thereof.

The leading feature of the design is the arrangement of the harrow-tooth bars relatively to the connecting cross-bars and the general shape of the frame.

The harrow-tooth bars A are arranged parallel to each other, and extending at right angles to these bars are cross-bars B. The ends of the bars A project at different lengths

from the outside cross-bars, and as these are of the same length where they project slightly on one side of the frame at the opposite side they extend outward beyond the frame to a greater extent, and thus the extreme ends of the bars A on each side are out of line. The cross-bars B have holes b through them at intervals to receive the harrow-tooth bars. Inclined bars C extend between the center bar B and the outer cross-bars.

What I claim is—

The design for a harrow-frame as herein shown and described.

In testimony whereof I affix my signature in presence of two witnesses.

GEORGE W. REAM.
